H. E. VAN NESS

YARN CLEANER

Original Filed June 8, 1922

INVENTOR
HENRY E. VAN NESS
BY
Robert W. Byerly
ATTORNEY

UNITED STATES PATENT OFFICE.

HENRY E. VAN NESS, OF ELMIRA, NEW YORK.

YARN CLEANER.

Original application filed June 8, 1922, Serial No. 566,721. Divided and this application filed February 8, 1924. Serial No. 691,569.

To all whom it may concern:

Be it known that I, HENRY E. VAN NESS, a citizen of the United States, residing at Elmira, in the county of Chemung and State 5 of New York, have invented certain new and useful Improvements in Yarn Cleaners, fully described and represented in the following specification and the accompanying drawing, forming a part of the same.

10 This invention relates to yarn cleaners for eliminating impurities, such as parts of seeds, parts of stems, slubs, specks and other particles from yarn before the yarn is woven into cloth, so that a superior quality of cloth 15 may be produced from comparatively inexpensive yarns.

A simple and effective device for this purpose is described and claimed in my co-pending application filed June 8, 1922, Serial No. 566,721, of which the present application is a division. The yarn cleaner described in the said original application provides means forming a slot located at one 25 side of the yarn and arranged to engage particles projecting from the yarn and to guide such particles away from the yarn. The present invention consists in providing such a slot between two acute edges and in certain features of construction and arrangement hereinafter particularly described and claimed.

In order that the invention may be clearly understood, I will describe in detail a yarn cleaner embodying the invention which is 35 illustrated in the annexed drawings, in which:—

Fig. 1 is a side elevation of the yarn cleaner; and

Figs. 2, 3, 4, 5 and 6 are enlarged views 40 of a cleaning unit of the yarn cleaner shown in Fig. 1, Fig. 2 being a side elevation, Fig. 3 a front elevation showing the bar sectioned on the line 3—3 of Fig. 2, Fig. 4 a transverse section on the line 4—4 of Fig. 2, Fig. 45 5 a side view with two of the cleaning members removed, and Fig. 6 a plan view.

The yarn cleaner illustrated in the drawings comprises a bar 10, on one end of which is mounted a tension device 13 of ordinary 50 construction. In alined relation along one side of the bar 10 are mounted the cleaning units 15. As the units are all alike, a description of one of them will suffice.

A cleaning unit 15 comprises two upper 55 cleaning members 20, 20' and two lower

cleaning members 30, 30'. The cleaning member 20 comprises a supporting portion or foot 21, an outwardly bent portion 22, an outwardly flaring ear 23, and a cleaning blade 24. The cleaning member 20' is similar to the member 20 and its parts are identified in the drawings by the same reference numbers as the parts of the member 20, a prime being added to each number. The lower cleaning member 30 comprises a supporting portion or foot 31 and a blade 34, while the lower cleaning member 30' has a similar foot 31' and a similar blade 34'.

The four cleaning members are secured to the bar 10 by screws 16 passing through 70 their feet. A removable spacing member 17 is placed between the feet 31, 31' of the members 30, 30'.

The upper blades 24, 24' are bevelled on the outside at 25, 25' to form acute cleaning 75 edges 26, 26'. These cleaning edges are curved as indicated in Figs. 1, 2 and 5. The lower blades 34, 34' are bevelled on the outside at 35, 35' so as to form acute cleaning edges 36, 36' which are curved somewhat 80 more sharply than the cleaning edges 26, 26'. The cleaning edges 26 and 36 lie in a common plane, and the cleaning edges 26' and 36' lie in a common plane. These planes are parallel and separated by a distance determined by the thickness of the spacing member 17. The distance between the planes should be substantially equal to the diameter of the yarn, so that the planes are tangential to the yarn at opposite sides thereof. In 90 order to adjust the units for use in connection with yarns of different diameters, a plurality of spacing members of different thicknesses may be provided.

The cleaning edge 26 is cut away at 95 and the front corner 28 of the cleaning edge 26' is turned in. Similarly the cleaning edge 36' is cut away at 37 and the front corner 38 of the cleaning edge 36 is turned in.

The edges 26 and 36 form between them 100 an opening or slot 40 which lies wholly at one side of the yarn. The slot 40 tapers inwardly from its entrance end 41 to a neck 42 of less width than the diameter of the yarn, and tapers outwardly from the neck 105 42 to its discharge end 43. The entrance end 41 of the slot 40 is immediately adjacent to the yarn A¹, while the discharge end 43 of the slot is some distance below the line of travel of the yarn. The opening or slot 40' 110

included between the edges 26' and 36' is similar to the slot 40.

In the operation of the cleaning device described, the yarn is passed around the tension device 13 and then drawn downward and forward between the ears 23, 23' of each unit until it extends in a straight horizontal line, passing between the blades 24 and 24' of each unit and between the turned-in corners 28, 38 of the blades 26' and 36 of each unit. It is then drawn continuously forward. The particles adhering to the yarn and projecting therefrom enter the slots 40, 40'. As the yarn is drawn forward, the particles pass along longitudinally in the slots 40, 40', being separated from the yarn at or about the time they reach the necks 42, 42'. The necks are, however, of such width that the particles being separated from the yarn 20 and the particles which have been separated are moved continuously forward through the necks and the outwardly tapering portions of the slots by the pressure of the particles behind them, which is caused by the 25 pull of the yarn. The particles are, therefore, continuously discharged from the lower ends of the slots.

What I claim is:

1. In a yarn cleaner for removing particles adhering to a traveling yarn, a cleaning unit comprising members having opposed spaced acute edges forming the guiding slot at one side of the yarn, the entrance end of said slot being immediately adjacent to the 30 yarn and the discharge end remote from the yarn, said slot tapering inwardly from its entrance end to a neck of less width than the diameter of the yarn and tapering outwardly from said neck toward its discharge end.
2. A yarn cleaner for removing particles adhering to a traveling yarn, comprising a blade having an acute edge, a second blade having an acute edge spaced from the edge of the first blade and forming therewith a 35 guiding slot extending in the general direction of the travel of the yarn but diverging from the line of travel so that its entrance end is immediately adjacent to the yarn and its discharge end is remote from the 40 yarn, and tapering inwardly from its entrance end to a minimum width less than the diameter of the yarn but sufficient to permit longitudinal travel of particles in the slot under the effect of the pull of the yarn 45 upon particles entering the slot, the portion of the slot whose width is less than the di-

ameter of the yarn being located wholly at one side of the yarn, and means for retaining said blades in fixed relation to each other during the operation of the cleaner. 60

3. A yarn cleaner for removing particles adhering to a traveling yarn, comprising a pair of parallel blades lying adjacent to opposite sides of the yarn and having acute operative edges inclined away from the line 65 of travel of the yarn, and a second pair of parallel blades having acute operative edges opposed to the edges of the first blades respectively and forming therewith slots tapering inwardly from their entrance ends. 70

4. A yarn cleaner for removing particles adhering to a traveling yarn, comprising a pair of parallel blades lying adjacent to opposite sides of the yarn and having acute operative edges inclined away from the line of 75 travel of the yarn, and a second pair of parallel blades having acute operative edges opposed to the edges of the first blades respectively and forming therewith slots tapering inwardly from their entrance ends. the 80 front corner of one of the operative edges of each pair of blades being turned inwardly.

5. A yarn cleaner for removing particles adhering to a traveling yarn, comprising an upper pair of parallel blades lying adjacent 85 to opposite sides of the yarn and having acute lower edges curving downwardly from the line of travel of the yarn, and a lower pair of parallel blades having acute curved edges opposed to the edges of the first blades 90 respectively and forming therewith curved slots tapering inwardly from their entrance ends. 95

6. A yarn cleaner for removing particles adhering to a traveling yarn, comprising an upper pair of parallel blades lying adjacent to opposite sides of the yarn and having acute lower edges curving downwardly from the line of travel of the yarn, and a lower pair of parallel blades having acute curved edges opposed to the edges of the first blades 100 respectively and forming therewith curved slots tapering inwardly from their entrance ends, the lower front corner of one of the upper blades being turned inwardly so as to lie adjacent to the upper side of the yarn and the upper front corner of one of the lower blades being turned inwardly so as to lie adjacent to the lower side of the yarn. 105

In testimony whereof I have hereunto set my hand.

HENRY E. VAN NESS.
